ANTENNA MOUNTING BRACKET

Bruno Zucconi, Alameda, Calif.
(1970 Republic Ave., San Leandro, Calif. 94577)

Filed Oct. 23, 1969, Ser. No. 19,681

Term of patent 14 years

Int. Cl. D8—03

U.S. Cl. D8—234

F i g. 1

F i g. 2

FIG. 1 is an isometric view of an antenna mounting bracket, the broken lines being for illustrative purposes only.

FIG. 2 is an isometric view of the antenna mounting bracket opposite side thereof.

FIG. 3 is a front elevational view thereof.

FIG. 4 is a view as seen in the drawing of line 4-4, FIG. 3.

FIG. 5 is a view as seen in the drawing of line 5-5, FIG. 3.

FIG. 6 is a rear elevational view as seen in the drawing of line 6-6, FIG. 5.

I claim:
The ornamental design for an antenna mounting bracket, as shown and described.

No references cited.
